ARTHUR R. MOSLER, OF NEW YORK, N. Y., ASSIGNOR TO A. R. MOSLER & COMPANY, OF MOUNT VERNON, NEW YORK, A CORPORATION OF NEW YORK.

SPARK-PLUG.

1,344,956.

Specification of Letters Patent. Patented June 29, 1920.

Application filed September 16, 1916. Serial No. 120,525.

To all whom it may concern:

Be it known that I, ARTHUR R. MOSLER, a citizen of the United States, and resident of the borough of Manhattan, in the city and 5 State of New York, have invented a new and useful Improvement in Spark-Plugs, of which the following is a specification.

This invention relates to an improvement in spark plugs and has for its object to provide a priming device which will be simple in construction; readily manipulated; and cheap to manufacture.

A practical embodiment of my invention is represented in the accompanying drawings, in which—

Figure 1 represents a side elevation of a spark plug, with my improved priming device applied thereto,

Fig. 2 represents a longitudinal central 20 section taken in the plane of the line A—A of Fig. 1, looking in the direction of the arrows,

Fig. 3 represents a horizontal section taken in the plane of the line B—B of Fig. 25 1, looking in the direction of the arrows,

Fig. 4 represents a detail longitudinal section of a modified form of insulating block,

Fig. 5 represents a detail side elevation of 30 the upper portion of an insulating block, and

Fig. 6 represents a detail front elevation of the same.

The spark plug comprises a base 1 having bores 2, 3, between which a seat 4 is formed 35 for the insulating block 5. The insulating block 5 comprises a reduced inner portion 6, a reduced outer portion 7 and an enlarged intermediate portion 8, the formation of which provides annular shoulders 9, 10, extending around the periphery of the block. The block 5 is secured to the base 1 by 40 means of a hollow bushing 11 having a screw threaded engagement with the bore 3.

A gasket 12 is interposed between the 45 bushing 11 and the shoulder 10, and a gasket 13 is interposed between the seat 4 and the shoulder 9, thereby forming a gas tight joint between the block and base.

The block 5 has a central bore 14 extending longitudinally therethrough, the ends of 50 which bore are flared as shown at 15 and 16. The flared end 16 forms a priming cup in the block itself.

A metal valve seat 17 may be interposed 55 between the bore 14 and the flare 16, be-

tween which seat and bore a packing ring 18 is inserted. An electrode 19 is mounted to move freely in the central bore, and is provided with a valve 20 fixed thereon in position to coact with the valve seat 17. The 60 inner end of the electrode 19, when in its normal position, projects inwardly beyond the bottom of the base 1 a sufficient distance so as to coöperate with the electrode 21 which is secured to the base 1 and bent inwardly toward the electrode 19, leaving a gap across which the spark jumps.

The outer end of the electrode 19 projects outwardly beyond the block and has a cap 22 slidably mounted thereon. This cap 22 70 is provided with diametrically opposed inwardly turned lugs 23, which are adapted to engage diametrically opposed recesses 24 formed in the block 5 at or near the outer end. The block also has cutaway portions 75 25 intermediate of the recesses 24, which are connected by an annular channel 26. The cutaway portions 25 allow the lugs 23 on the cap 22 to pass to the channel 26 whence they are turned until they arrive at their respective recesses, thus locking the cap on the block 5.

A spring 27 is interposed between the cap and valve on the electrode 19, so that the valve will be firmly pressed on its seat and 80 the lugs on the cap held securely in their recesses.

The cap 22 is also provided with a binding post 28, which is screw threaded for the reception of a thumb nut 29.

The upper end of the electrode 19 is split, as at 30, and spread apart, so as to prevent the electrode from slipping through the cap 22 when removed from the block 5, and, at the same time, affording a means for removing and holding the electrode by the cap.

In the form shown in Fig. 4, the insulating block 5 has a seat 31 ground directly in the block, upon which seat the valve rests to close the bore.

In using the device, assuming the plug to be in its operative position, the cap 22 is first forced downwardly against the tension of the spring 27 until the lugs 23 are free of their recesses 24 and in the path of the 105 annular channel 26, when the cap may be turned or rotated on the electrode until the lugs 23 reach the cutaway portions 25 whereupon the cap and electrode will be free to be removed leaving the bore 14 with its flared 110

- end 16 open and exposed. The flared end 16 serves as a priming cup into which a priming fluid may be introduced and passed through the bore 14 into the cylinder of the engine (not shown). After the priming fluid is injected, the electrode may be inserted in the bore 14, seating the valve 20, and placing the cap 22 with its lugs 23 in position to pass downwardly on the block 5 at the cutaway portions 25. The further downward movement of the cap 22 compresses the spring 27 until the lugs 23 reach the channel 26, then by turning or rotating the cap upon the electrode until the lugs 23 10 reach their respective recesses 24, the pressure may be relieved, whereupon the lugs 23 will engage the recesses, thus locking the cap 22 in its place on the block and the valve 20 on its seat 17.
- 15 20 What I claim is:—
1. A spark plug comprising a block of insulating material having a longitudinal bore flared at its upper end to form a priming cup, an electrode movable in said bore, a valve on said electrode engaging said block at the junction of the flared portion and longitudinal bore, a cap removably engaging the block for covering the bore, and means interposed between the cap and valve 25 for yieldingly holding the valve closed on the bore.
  2. A spark plug comprising a block of insulating material having a longitudinal bore flared at its upper end to form a priming cup, a valve seat in the block at the junction of the flared portion and longitudinal bore, an electrode movable in said bore, a valve on said electrode arranged to coact with said seat in the block for closing the bore, a cap 30 removably engaging the block for covering the flared portion and valve, and means interposed between the cap and valve for yieldingly holding the valve on its seat.
  3. A spark plug comprising a block of insulating material having a longitudinal bore terminating in a flared portion at each end, the flared portion at the upper end forming a priming cup, a valve seat in the block at the junction of the upper flared portion and longitudinal bore, an electrode movable in said bore, a valve on said electrode arranged to coact with said seat in the block for closing the bore, a cap removably engaging the block for covering the flared portion and 35 valve and means interposed between said cap and valve for yieldingly holding the valve on its seat.
  4. A spark plug comprising a block of insulating material having exterior annular
- 50 recesses in its upper end and a longitudinal bore flared at its upper end to form a priming cup, a valve seat in the block at the junction of the upper flared portion and longitudinal bore, an electrode movable in said bore, a valve on said electrode arranged to coact with said seat in the block for closing the bore, a cap provided with lugs adapted to engage said recesses for covering the flared portion and valve, and means interposed between said cap and valve for yieldingly holding the valve on its seat. 55
- 55 60 65 70 75 80 85 90 95 100 105 110 115
5. A spark plug comprising an insulating block having exterior recesses and cutaway portion formed in its outer end, a bore therethrough having its end flared to form a priming cup, a valve seat interposed between said flared portion and the bore, a cap provided with lugs adapted to removably engage said recesses for covering the priming cup and valve seat, an electrode movable in said bore, a valve on said electrode arranged to coact with said seat for closing said bore, and means interposed between the cap and valve for yieldingly holding the valve on its seat.
  6. A spark plug comprising a block of insulating material having exterior recesses in its upper end and a longitudinal bore flared at its upper end to form a priming cup, a valve seat in the block at the junction of the flared portion and longitudinal bore, an electrode movable in said bore, a valve on said electrode arranged to coact with said seat in the block for closing the bore, a cap provided with lugs adapted to engage said recesses for covering the flared portion and valve, and a common means interposed between said cap and valve for yieldingly holding the valve on its seat and the lugs in their recesses in the block.
  7. A spark plug comprising a block of insulating material having a longitudinal bore flared at its upper end to form a priming cup, an electrode movable in said bore, a valve on said electrode engaging said block for closing the bore, a cap slidable on the electrode and adapted to removably engage the block for covering the valve and bore, the outer end of the electrode being split longitudinally and the portions slightly spread apart to frictionally engage the cap to prevent its unintentional displacement when disengaged from the block.
- In testimony, that I claim the foregoing as my invention, I have signed my name this 24th day of August, 1916.

ARTHUR R. MOSLER.
